UNITED STATES PATENT OFFICE.

CHARLES A. WARLAND, OF PAWTUCKET, RHODE ISLAND, ADMINISTRATOR
OF ISAAC LINDSLEY, DECEASED.

STRAW MATTING OR SIMILAR FABRIC.

SPECIFICATION forming part of Letters Patent No. 425,090, dated April 8, 1890.

Application filed October 14, 1889. Serial No. 327,004. (No model.)

To all whom it may concern:

Be it known that ISAAC LINDSLEY, deceased, late a citizen of the United States, residing at Pawtucket, in the county of Providence, in the State of Rhode Island, invented a new and useful Improvement in Straw Matting and Similar Fabrics, of which the following is a specification.

The nature of the invention consists in a straw matting or similar fabric having a selvage of improved construction, as hereinafter fully set forth.

Figure 1 represents a plan view of a piece of straw matting having its selvages woven according to the improvement, a portion of the filling being left open to show the manner of weaving. Fig. 2 represents a plan view of the same, showing modifications in the selvage, the filling being all left open to show the manner of weaving. Fig. 3 is a transverse section showing the curved filling-strips and the straightly-drawn main warp-threads. Fig. 4 is an enlarged longitudinal section showing the relative position and arrangement of the straightly-drawn main warp-threads of the selvage and the curved binding warp-threads at the side of the straightly-drawn main warp-threads.

Heretofore in the manufacture of straw matting and similar fabrics it has been customary to turn the end of each alternate filling-strip backward over the fabric to form a selvage; but when so turned the edge of the fabric was necessarily thickened, and thus rendered liable to rapid wear by projecting above the general surface of the matting when laid upon the floor; and it is the object of this improvement to produce a practically-bound selvage upon such fabrics without producing the thickened ridge at the edge of the fabric, as when the alternate filling-strips are turned backward over the fabric and secured in position by means of a main warp-thread, as heretofore.

In the accompanying drawings, A represents a piece of straw matting having opposite selvages $b b'$. $c c$ are the main warp-threads, which are preferably made of larger size than the binding warp-threads d , and $e e$

are the filling straws or strips. The warp-threads $c c$ are so drawn that they will have a practically straight direction through the fabric, the filling-strips $e e$ curving over and under the same, as shown in the section, Fig. 3, while the binding warp-threads will lie alongside of the outer main warp-thread c , and instead of lying straight in the fabric will curve over and under the filling-strips $e e$, as shown in Fig. 4, so that the curved binding warp-threads d will be considerably longer when extended than the straightly-drawn main warp-thread c .

In weaving the selvage in accordance with this improvement a single binding warp-thread d may be employed, as shown at the selvage b in Fig. 1; or two or more binding warp-threads d may be employed at opposite sides of the main warp-thread c , as shown at the opposite selvage b' , and instead of applying the binding warp-thread to the outer main warp-thread alone the same can also be applied to an adjoining inner main warp-thread c' , as shown at the selvage b^2 in Fig. 2.

In weaving the selvage for what is known as "three-leaf twill," in which three harnesses are employed, two or more binding warp-threads are employed at the side of the main warp-thread, in order to properly fasten all of the filling-strips, such an arrangement of warp-threads being shown at the selvage b^3 in Fig. 2, in which the binding warp-threads $d d$ are made to pass the one over and the other under the filling-strips at the side of the warp-thread c .

What is claimed is—

1. In the selvage of straw matting or similar fabric, the combination, with the filling-strips and a straightly-drawn main warp-thread which causes the bending of the filling-strips, of a curved binding warp-thread which is contiguous to the main warp-thread and is curved back and forth around the opposite filling-strips to bind the same against the main warp-thread, substantially as described.

2. In the selvage of straw matting or similar fabric, the combination, with the filling-strips and a straightly-drawn main warp-

85

95

thread which causes the bending of the filling-strips, of a binding warp-thread which curves back and forth around the opposite filling-strips to bind the same against the 5 main warp-thread, substantially as described.

3. In the selvage of straw matting or similar fabric, the combination, with the filling-strips and a straightly-drawn main warp-thread which causes the bending of the filling-strips, of duplicate-curved binding warp- 10

threads at the side of the main warp-thread, the one passing over and the other under each filling-strip, substantially as described.

CHAS. A. WARLAND,
*Administrator of the estate of Isaac Lindsley,
deceased.*
